UNITED STATES PATENT OFFICE.

JOHN B. HUNT, OF TRENTON, NEW JERSEY.

WINDOW HOLDING AND ANTIRATTLING DEVICE.

No. 853,697.

Specification of Letters Patent.

Patented May 14, 1907.

Application filed April 5, 1906. Serial No. 310,000.

To all whom it may concern:

Be it known that I, JOHN B. HUNT, a citizen of the United States, residing at Trenton, in the county of Mercer, State of New Jersey, have invented a new and useful Window Holding and Antirattling Device, of which the following is a specification.

My invention consists of an improvement in a window-holding and antirattling device, 10 the same embodying a roller, a shaft therefor, ears forming the bearings of said shaft, a stub connected with said ears and forming with the same a shoulder and a spiral or coiled spring which has one end fitted on said 15 stub and adapted to abut against said shoulder, the other end of said spring being adapted to bear against the base of the recess in the sash frame which receives the device, the stub serving to guide and steady the roller 20 and prevent lateral or irregular motions thereof and avoiding the employment of a casing for the spring and a lining or stop in said recess, while a portion of the spring continues from the terminal of the stub and is 25 free to contract and expand without liability to be interfered with by the wall of said recess.

Figure 1 represents a perspective view of a device embodying my invention. Fig. 2 30 represents a longitudinal section thereof. Fig. 3 represents a side elevation of the device in position in a sash frame. Fig. 4 represents a partial section and partial elevation of the device showing a form of connecting 35 the spring with the stub. Fig. 5 represents a longitudinal section of a modification, the roller being omitted.

Similar letters of reference indicate corresponding parts in the figures.

Referring to the drawings: A designates a 40 roller and B the shaft or axle thereof. C designates ears with which the ends of said axle are connected as the bearings thereof. Extended rearwardly from said ears is the stub D which is integral therewith, being preferably formed together of cast metal, the stub being of such diameter that the place of connection of the same with said ears forms the shoulder E.

F designates a spiral or coiled spring which 50 has one end portion fitted on the stub D, the end of the same bearing against the shoulder E while the opposite end is free, it being noticed that the stub is considerably shorter

than the spring, whereby the latter has full 55 range of motion when in use without being controlled or stopped by said stub.

It will be seen that a recess is formed in a sash frame and the device inserted thereinto, the inner end of the spring bearing against 60 the base of said recess and the spring being compressed or contracted so that it will exert pressure on the shoulder E and consequently on the roller in which condition the latter rests against and rides upon the adjacent 65 portion of the window frame, so as to provide friction between the contacting parts and prevent rattling of the sash without, however, interfering with the motions of the sash in the raising and lowering of the same. It 70 will be seen also that the spring is prevented from slipping forward of the shoulder E and that the wall of said recess freely incloses the spring and prevents improper bending of the 75 same and the stub occupies the interior of the spring, it is held and guided true therein, so that the roller is caused to contact uniformly with the adjacent portion of the window frame and prevented from irregular and wabbling motions thereon, it being also noticed that the stub is short in its nature, that is, it is of less length than the spring, whereby in the compression of the latter the stub does not interfere with the same, while to all intents, said stub is sufficiently held by the 85 spring. It will be seen further that when desired a stronger spring may be employed in which case the coils of its forward portion may be reduced in diameter so as to properly embrace the stub, while bearing against the 90 shoulder or should a lighter spring be desired, the coils of its forward end may be enlarged for the same purpose.

Should it be desired to prevent any possible rotation of the spring on the stub, the latter 95 is formed in its side with an opening G and the spring has its adjacent end provided with a lip H which is adapted to enter said opening G, thus in a measure interlocking the spring with the stub.

In Fig. 5, I show the stub as made separate from the ears, but connected therewith by the rivet J which passes through said stub and the connecting back plate of the ears and has its ends headed on said stub and plate 100 without however producing different results in the operation of the roller, the construction however being such that the ears C and

back connecting plate may be made of lighter material than the stub D, but in either case the spring F and the ears C occupy the opening or recess in the sash frame without a covering, such as a lining therein as the wall of said opening or recess provides of itself such covering and the back of said recess providing the seat for the inner terminal of the spring. It will be noticed also that the ears C form the bearings for the shaft or axle B, on which the roller A is mounted, the end of said shaft being headed on the exterior of said ears. By this provision the device is wider at the places of the ends of said shaft than the diameter of the spring F. Consequently while the device occupies the recess directly in the sash frame as has been stated, the side of the coils of the spring does not contact with the wall of said recess, but on the contrary is free therefrom, whereby while the ears C may be close to said wall, said coils are removed from contact therefrom, and so the spring is enabled to expand

and contract without interference of said wall.

Having thus described my invention what I claim as new and desire to secure by Letters Patent, is:

In a window holding and anti-rattling device, a coiled spring, a roller, ears, an axle secured to the latter and carrying said roller, a stub connected with said ears and extending rearwardly therefrom, and a shoulder intermediate of said ears and stub, only one portion of said spring being fitted on said stub, the other portion projecting freely therefrom, the device being adapted to freely occupy a recess directly in a sash frame, the free portion of said spring being adapted to be removed from controlling contact with the side wall of said recess.

JOHN B. HUNT.
